[57] CLAIM

The ornamental design for a needle disposal kit, as shown and described.

DESCRIPTION

FIG. 1 is a perspective view of a needle disposal kit, showing our new design, with the sealing component in open position;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof, the right side elevational view being a mirror image; and,

FIG. 7 is a top plan view thereof, with the sealing component in closed position.

FIG. 1

FIG. 2

FIG. 3

FIG. 4

FIG. 5
